UNITED STATES PATENT OFFICE

155,145

DESIGN FOR A GAS METER

Edward R. Gilmore, Pittsburgh, Pa., assignor to
Rockwell Manufacturing Company, Pittsburgh,
Pa., a corporation of Pennsylvania

Application September 19, 1947, Serial No. 141,474

Term of patent 14 years

(Cl. D52—1)

To all whom it may concern:

Be it known that I, Edward R. Gilmore, a citizen of the United States, residing at Pittsburgh, in the county of Allegheny and State of Pennsylvania, have invented a new, original, and ornamental Design for Gas Meter, of which the following is a specification, reference being had to the accompanying drawing, forming a part thereof.

Figure 1 is a front elevation of a gas meter, showing my new design;

Figure 2 is a side elevation of the gas meter of Figure 1;

Figure 3 is a rear elevation of the gas meter of Figure 1; and

Figure 4 is a top plan view of the gas meter of Figure 1.

The side of the gas meter not shown is the same in appearance as the side shown in Figure 2.

The characteristic features of my design reside in the portion shown in solid lines.

I claim:

The ornamental design for a gas meter, substantially as shown and described.

EDWARD R. GILMORE.
